[57] **ABSTRACT**

A method of stimulating the central nervous system
and of enhancing behavior by administering an effective
amount of a compound of the formula

and pharmaceutically acceptable acid addition salts
thereof wherein n is 0, 1 or 2, R is hydrogen or lower
alkyl of up to four carbons, R₁ is lower alkyl of up to
four carbon atoms, and R and R₁ together with the
nitrogen atom to which they are bonded are
piperidino, morpholino or pyrrolidino.

7 Claims, No Drawings

METHOD OF ADMINISTERING CENTRAL NERVOUS SYSTEM ACTIVE COMPOUNDS

BACKGROUND OF THE INVENTION

Compounds which stimulate the central nervous system and which enhance behavior have been the subject of considerable research. Amphetamine, for example, has been suggested as such a compound but is objectionable in that its use is subject to abuse and, in geriatric cases, it has the undesired effect of reducing appetite.

OBJECTS OF THE INVENTION

It is, accordingly, an object of the present invention to provide a method for stimulating the central nervous system and enhancing behavior without the side effects attributed to amphetamine-type compounds. Another object is to provide a method for the administration of compounds which achieve the foregoing objects. A further object is to provide dosage levels and formulations for the administration of these compounds. These and other objects of the present invention will be apparent from the following description.

DETAILED DESCRIPTION

It has now been found that the central nervous system is stimulated and behavior is enhanced by administering an effective amount of a compound of the general formula

and pharmaceutically acceptable acid addition salts thereof wherein n is 0, 1 or 2, R is hydrogen or lower alkyl of up to four carbon atoms, R_1 is lower alkyl of up to four carbon atoms, and R and R_1 together with the nitrogen atom to which they are bonded are piperidino, morpholino or pyrrolidino.

Examples of typical lower alkyl-substituted amine compounds wherein the cycloalkyl ring may be cyclopentyl, cyclohexyl or cycloheptyl are as follows:

2-(mono-lower alkylaminomethyl)cycloalkyl p-aminobenzoate, e.g., 2-(monomethylaminomethyl)cycloalkyl p-aminobenzoate, and 2-(di-lower alkylaminomethyl)cycloalkyl p-aminobenzoate, e.g., 2-(methylethylaminomethyl)cycloalkyl p-aminobenzoate, 2-(diethylaminomethyl)cycloalkyl p-aminobenzoate, 2-(methylpropylaminomethyl)cycloalkyl p-aminobenzoate, 2-(dipropylaminomethyl)cycloalkyl p-aminobenzoate and 2-(ethylpropylaminomethyl)cycloalkyl p-aminobenzoate.

Preferred compounds of the lower alkyl-substituted amines are those wherein both R and R_1 are lower alkyl and wherein the total number of carbon atoms in R and R_1 is at least three. More preferably, the compounds are those wherein the total number of carbon atoms in R and R_1 is four. Most preferred is the compound wherein both R and R_1 are ethyl.

When any of the foregoing compounds are given to rats orally at a dose level of 3 mg/kg, increased motor activity is observed. One or more of the foregoing compounds may be administered to humans orally or by injection two or three times daily in doses of from 1 to 50 mg, preferably from about 5 to about 20 mg. The administration of the foregoing compounds is especially suitable for geriatric use as the compounds are not anorectic agents.

The active compounds of the present invention may be utilized in compositions such as tablets, capsules, solutions or suspensions containing up to about 50 mg per unit of dosage of a compound or mixture of compounds of the present invention or a physiologically acceptable acid addition salt thereof. The compounds of the present invention may be compounded in conventional manner with a physiologically acceptable vehicle or carrier, excipient, binder, preservative, stabilizer, flavor, etc., as called for by accepted pharmaceutical practice.

The compounds of the present invention may be prepared by reacting a 2-dialkylaminomethylcycloalkanol with a p-nitrobenzoyl halide, followed by reduction of the nitro group to an amino group.

The desired 2-dialkylaminomethylcycloalkanols are obtained by condensing a cycloalkanone with paraldehyde or formaldehyde and a dialkylamine and reducing the dialkylaminomethylcycloalkanone to the corresponding dialkylaminomethylcycloalkanol.

In those cases where the desired final product is a monoalkylaminomethylcycloalkyl ester, the desired product is obtained by hydrogenolysis of the corresponding benzylalkylaminomethylcycloalkyl ester.

In those cases where

represents a heterocyclic ring, the desired products are obtained by condensing the heterocycle

with formaldehyde or paraldehyde and a cycloalkanone, followed by reduction to the cycloalkanol, esterification and reduction of the p-nitrobenzoyl ester thus obtained.

The compounds of the present invention may be obtained as mixtures of stereoisomers (cis and trans) and the individual isomers may be separated and isolated according to techniques known in the art. The cis or trans form of the specific compounds may then be further resolved into individual enantiomorphs.

The compounds described herein form salts which are also part of this invention. The salts include acid addition salts, particularly the non-toxic pharmaceutically acceptable salts. The salts may be formed by reacting the compounds of the present invention with a variety of inorganic or organic acids providing acid addition salts including, for example, hydrohalides (especially hydrochloride and hydrobromide), sulfate, nitrate, borate, phosphate, oxalate, tartrate, maleate, citrate, acetate, ascorbate, succinate, benzenesulfonate, methanesulfonate, cyclohexanesulfonate, toluenesulfonate and the like. The acid addition salts frequently provide a convenient means for isolating the product,

e.g., by forming the precipitating the salt in a medium in which the salt is insoluble, then after separation of the salt, neutralizing with a base such as barium hydroxide or sodium hydroxide, to obtain the free base of formula I. Other salts may then be formed from the free base by reaction with an equivalent of acid.

The following examples illustrate the present invention without, however, limiting the same thereto. All temperatures are expressed in degrees Centigrade.

EXAMPLE 1

2-(Diethylaminomethyl)cyclohexyl p-aminobenzoate hydrochloride

a. 2-(Diethylaminomethyl)cyclohexanone hydrochloride

To a 2 liter flask is added 109 grams of diethylamine hydrochloride, 200 grams of cyclohexanone, 30 grams of paraformaldehyde and 400 ml of glacial acetic acid. The mixture is stirred and slowly heated to 60°. The exothermic reaction that occurs is controlled by cooling the reaction mixture. The solution is heated at 70°-75° for 2.5 hours and then cooled and diluted with 2.5 liters of anhydrous ether. The product separates as an oil. The supernatant liquid is decanted and the residual oil triturated with 300 ml of anhydrous ether to give a semi-solid product, which is used without further purification in part b.

b. 2-(Diethylaminomethyl)cyclohexanol

A solution of 43 grams of 2-(diethylaminomethyl) cyclohexanone (prepared in part a) in 200 ml of ethanol, to which is added 1 gram of platinum oxide, is shaken with hydrogen at 50 psi in a Parr hydrogenation apparatus. The hydrogen uptake ceases after about 2 hours. The mixture is filtered and the filtrate is concentrated under reduced pressure to remove the solvent. The residue is dissolved in water and made strongly alkaline by the addition of sodium hydroxide pellets. The liberated base is extracted with ether and the ether dried over anhydrous magnesium sulfate. The solution is then concentrated and the residue fractionally distilled to yield the desired product, bp 88-90 at 2 mm.

Alternatively the aminoketone may be converted to the aminoalcohol by reduction with sodium borohydride in methanol (see Example 2, part b).

c. 2-(Diethylaminomethyl)cyclohexyl p-nitrobenzoate hydrochloride

A solution of 37 grams of 2-(diethylaminomethyl) cyclohexanol in 100 ml of chloroform is added dropwise to a stirred solution of 37 grams of p-nitrobenzoyl chloride in 200 ml of chloroform while maintaining the temperature at 15°-25°. The solution is then refluxed for 1 hour and the bulk of the solvent removed by distillation under reduced pressure. The solidified residue is triturated with 300 ml of ether and the mixture filtered to yield the crude product. After recrystallization from 200 ml of acetonitrile the product weighs 43 grams and melts at 184°-186°.

d. 2-(Diethylaminomethyl)cyclohexyl p-aminobenzoate hydrochloride

To a warm solution of 20 grams of 2-(diethylaminomethyl)cyclohexyl p-nitrobenzoate hydrochloride in 250 ml of ethanol, there is added 3 grams of 5 percent palladium-on-carbon. The mixture is then hydrogenated at 50 psi of hydrogen in a Parr

hydrogenation apparatus. The cooled mixture is filtered and concentrated under reduced pressure to remove the solvent. The oily residue is triturated with 500 ml of ether, yielding 35 grams of crude product, melting at 192°-194°. After crystallization from ethanol-ether and from acetonitrile the product melts at about 197°-198°.

EXAMPLE 2

10 2-(Diethylaminomethyl)cyclopentyl p-aminobenzoate hydrochloride

a. 2-(Diethylaminomethyl)cyclopentanone hydrochloride

15 A mixture of 170 grams of cyclopentanone, 110 grams of diethylamine hydrochloride, 30 grams of paraformaldehyde and 400 ml of glacial acetic acid is stirred and heated slowly to 70°. The solution is maintained at 70°-75° for 2.5 hours, cooled to room temperature and diluted with 2 liters of ether. The oily precipitate is triturated twice with ether and the semi-solid product suspended in a mixture of ethyl acetate and ether. The crude product is filtered, dried and washed with cold acetone to yield 147 grams of product melting at 119°-121°.

b. 2-(Diethylaminomethyl)cyclopentanol

A suspension of 103 grams of 2-(diethylaminomethyl)-cyclopentanone hydrochloride in 75 ml of water is layered with ether and treated with 30 75 grams of potassium carbonate in portions. The organic layer is separated and the slurry extracted with 50 ml portions of ether (3 times). The combined ether extracts are dried over anhydrous magnesium sulfate, filtered, and the filtrate added portionwise to a stirred

35 solution of 50 grams of sodium borohydride in 1 liter of methanol, while the temperature is maintained at 20°-30. The solution is stirred for 2 hours at room temperature and is then concentrated under reduced pressure. The residue, after removal of the solvent, is 40 treated with 100 ml of water and the mixture extracted with ether. The dried ether solution is concentrated and the residue fractionated under reduced pressure to yield the desired 2-(diethylaminomethyl)cyclopentanol boiling at 76°-78° at 2 mm.

c. 2-(Diethylaminomethyl)cyclopentyl p-nitrobenzoate hydrochloride

Following the procedure of Example 1c, but substituting an equivalent amount of 2-(diethylaminomethyl)cyclopentanol for the 2-(diethylaminomethyl)cyclohexanol, there is obtained the desired 2-(diethylaminomethyl)cyclopentyl p-nitrobenzoate hydrochloride, melting at 156°-158° after crystallization from isopropanol.

d. 2-(Diethylaminomethyl)cyclopentyl p-aminobenzoate hydrochloride

Following the procedure of Example 1d, but substituting an equivalent amount of 2-(diethylaminomethyl)cyclopentyl p-nitrobenzoate hydrochloride for the 2-(diethylaminomethyl) cyclohexyl p-nitrobenzoate hydrochloride, there is obtained the desired 2-(diethylaminomethyl)cyclopentyl p-aminobenzoate hydrochloride, melting at about 185°-187° after crystallization from ethanol.

EXAMPLE 3

2-(Dimethylaminomethyl)cycloheptyl p-aminobenzoate hydrochloride

a. 2-(Dimethylaminomethyl)cycloheptanone

A mixture of 112 grams of cycloheptanone, 75 grams of 40 percent aqueous formaldehyde and 81 grams of dimethylamine hydrochloride is stirred vigorously and heated to reflux in an atmosphere of carbon dioxide. Water and unreacted ketone are removed by distillation under reduced pressure. The residue is dissolved in water and the free base liberated by the addition of sodium carbonate. The mixture is extracted with ether and the ether dried over anhydrous potassium carbonate. After removal of the ether, the residue is purified by distillation under reduced pressure, boiling at 105° - 107° at 2.5 mm.

b. 2-(Dimethylaminomethyl)cycloheptyl p-aminobenzoate hydrochloride

Following the procedure of Example 2, but substituting an equivalent amount of 2-(dimethylaminomethyl)cycloheptanone for the 2-(diethylaminomethyl)cyclopentanone in part b), there is obtained the desired 2-(dimethylaminomethyl)cycloheptyl p-aminobenzoate hydrochloride.

EXAMPLE 4

2-(Methylaminomethyl)cyclohexyl p-aminobenzoate hydrochloride

a. 2-(Methylbenzylaminomethyl)cyclohexanone hydrochloride

A mixture of 93 grams of cyclohexanone, 74.6 grams of methylbenzylamine hydrochloride and 14.3 grams of paraformaldehyde in 180 ml. of acetic acid is heated at 75° for 2.5 hours. The reaction is exothermic initially, and cooling is necessary to maintain the temperature at 75°. The reaction mixture is cooled, and 1.25 liters of ether is added with stirring. The oil, which separates, is dissolved in 400 ml. of acetone and 400 ml. of ether added. The product, which crystallizes upon cooling overnight, melts at 145°-146°.

b. 2-(Methylbenzylaminomethyl)cyclohexanol

Following the procedure of Example 2b but substituting an equivalent amount of 2-(methylbenzylaminomethyl)cyclohexanone hydrochloride for the 2-(diethylaminomethyl)cyclopentanone hydrochloride, there is obtained the desired 2-(methylbenzylaminomethyl)cyclohexanol, boiling at 153°-154° at 2 mm.

c. 2-(Methylbenzylaminomethyl)cyclohexyl p-nitrobenzoate hydrochloride

Following the procedure of Example 2c, but substituting an equivalent amount of 2-(methylbenzylaminomethyl)cyclohexanol for the 2-(diethylaminomethyl)cyclopentanol, there is obtained the desired 2-(methylbenzylaminomethyl)cyclohexyl p-nitrobenzoate hydrochloride. The mixture of cis and trans melt at about 180°-182°. Fractional crystallization of this mixture of isomers yields a low melting isomer, melting at 183°-185°, and a high melting isomer, melting at 238°-239°.

d. 2-(Methylaminomethyl)cyclohexyl p-aminobenzoate hydrochloride

Following the procedure of Example 1d but substituting an equivalent amount of 2-(benzylaminomethyl)cyclohexyl p-nitrobenzoate hydrochloride (m.p. 238°-239°) for the 2-(diethylaminomethyl)cyclohexyl p-nitrobenzoate hydrochloride, there is obtained the desired 2-

(methylaminomethyl)cyclohexyl p-aminobenzoate hydrochloride, melting at about 163°-165°, after crystallization from acetonitrile.

EXAMPLE 5

2(1-Piperidinylmethyl)cyclohexyl p-aminobenzoate hydrochloride

a. 2-(1-Piperidinylmethyl)cyclohexanone

A stirred mixture of 300 grams of cyclohexanone and 85 grams of piperidine is cooled and treated with 85 ml. of concentrated hydrochloric acid in portions, while the temperature of the mixture is maintained below 40°. The reaction mixture is then cooled to 20°, and 81 grams of aqueous formaldehyde solution (37 percent) is added. The mixture is heated at 80°-85° and maintained at this temperature for 30 minutes. The solution is cooled, diluted with water and extracted several times with ether. The aqueous solution is cooled, layered with ether and made strongly alkaline by the addition, in portions, of about 200 grams of potassium carbonate. The ether layer is separated and the aqueous layer extracted several times with ether. The combined ether extracts are dried, filtered and concentrated to yield the desired 2-(1-piperidinylmethyl)cyclohexanone as an oil.

b. 2-(1-Piperidinylmethyl)cyclohexanol

To a stirred solution of 50 grams of sodium borohydride in 1.5 liters of methanol, there is added, dropwise, 180 grams of 2-(1-piperidinylmethyl)cyclohexanone, maintaining the temperature at about 35° - 40° with cooling. The solution is refluxed for 1 hr. and is then concentrated to remove the solvent. The residue is treated with 100 ml. of water and the mixture extracted several times with ether. The combined ether extracts are dried, filtered and concentrated. The residue is fractionally distilled to yield the desired 2-(1-piperidinylmethyl)cyclohexanol, boiling at 105° - 107° at 2 mm.

c. 2-(1-Piperidinylmethyl)cyclohexyl p-nitrobenzoate hydrochloride

Following the procedure of Example 1c but substituting an equivalent amount of 2-(1-piperidinylmethyl)cyclohexanol for the 2-(diethylaminomethyl)cyclohexanol, there is obtained the desired 2-(1-piperidinylmethyl)cyclohexyl p-nitrobenzoate hydrochloride, melting at 191 - 219°. The mixture of isomers is separated by fractional crystallization from dimethyl formamide to give two isomers, one melting at 249°-250° (dec) and the more soluble isomer melting at about 194°-196°.

d. 2-(1-Piperidinylmethyl)cyclohexyl p-aminobenzoate hydrochloride

Following the procedure of Example 1d but substituting an equivalent amount of 2-(1-piperidinylmethyl)cyclohexyl p-nitrobenzoate hydrochloride (m.p. 249° - 250°) for the 2-(diethylaminomethyl)cyclohexyl p-nitrobenzoate hydrochloride, there is obtained 2-(1-piperidinylmethyl)cyclohexyl p-aminobenzoate hydrochloride, melting at 220° - 222°, after crystallization from acetonitrile. Following the procedure of Example 1d but substituting an equivalent amount of 2-(1-piperidinylmethyl)cyclohexanol p-nitrobenzoate hydrochloride (m.p. 194° - 196°) for the 2-(diethylaminoethyl)-cyclohexyl p-nitrobenzoate

hydrochloride, there is obtained 2-(1-piperidinylmethyl)cyclohexyl p-aminobenzoate hydrochloride, melting at 177° - 179°, after crystallization from acetonitrile, followed by crystallization from ethanol.

EXAMPLE 6

2-(1-Pyrrolidinylmethyl)cyclohexyl p-aminobenzoate hydrochloride

a. 2-(1-Pyrrolidinylmethyl)cyclohexanone

Following the procedure of Example 5a, but substituting an equivalent amount of pyrrolidine for the piperidine, there is obtained the desired 2-(1-pyrrolidinylmethyl)cyclohexanone.

b. 2-(1-Pyrrolidinylmethyl)cyclohexanol

Following the procedure of Example 5b, but substituting an equivalent amount of 2-(1-pyrrolidinylmethyl)cyclohexanone for the 2-(1-piperidinylmethyl)cyclohexanone, there is obtained the desired 2-(1-pyrrolidinylmethyl)cyclohexanol, boiling at 92° - 95° at 2 mm.

c. 2-(1-Pyrrolidinylmethyl)cyclohexyl p-aminobenzoate hydrochloride

Following the procedure of Example 1 but substituting an equivalent amount of 2-(1-pyrrolidinylmethyl)cyclohexanol for the 2-(diethylaminomethyl)cyclohexanol, there is obtained the desired 2-(1-pyrrolidinylmethyl)cyclohexyl p-aminobenzoate hydrochloride, melting at 188° - 190°, after crystallization from acetonitrile.

EXAMPLE 7

2-(4-Morpholinylmethyl)cyclohexyl p-aminobenzoate hydrochloride

a. 2-(4-Morpholinylmethyl)cyclohexanone hydrochloride

Following the procedure of Example 1a, but substituting an equivalent amount of morpholine hydrochloride for the diethylamine hydrochloride, there is obtained the desired 2-(4-morpholinylmethyl)cyclohexanone hydrochloride, melting at 144° - 146°.

b. 2-(4-Morpholinylmethyl)cyclohexanol

Following the procedure of Example 2b, but substituting an equivalent amount of 2-(4-morpholinylmethyl)cyclohexanone hydrochloride for the 2-(diethylaminomethyl)cyclopentanone hydrochloride, there is obtained the desired 2-(4-morpholinylmethyl)cyclohexanol, boiling at 120° - 122° at 2 mm.

c. 2-(4-Morpholinylmethyl)cyclohexyl p-nitrobenzoate hydrochloride

Following the procedure of Example 1c, but substituting an equivalent amount of 2-(4-morpholinylmethyl)cyclohexanol for the 2-(diethylaminomethyl)cyclohexanol, there is obtained the desired 2-(4-morpholinylmethyl)cyclohexyl p-nitrobenzoate hydrochloride, melting at about 191° - 202°. This mixture of isomers is separated by fractional crystallization from acetonitrile to yield two isomers, one melting at 248° - 250° (dec) and the second isomer melting at 199° - 201° (dec.).

d. 2-(4-Morpholinylmethyl)cyclohexyl p-aminobenzoate hydrochloride

Following the procedure of Example 1d, but substituting an equivalent amount of 2-(4-morpholinylmethyl)cyclohexyl p-nitrobenzoate hydrochloride

(m.p. 248° - 250°) for the 2-(diethylaminomethyl)cyclohexyl p-nitrobenzoate hydrochloride, there is obtained the 2-(4-morpholinylmethyl)cyclohexyl p-aminobenzoate hydrochloride melting at 181° - 183° after crystallization from acetonitrile.

Similarly, by using an equivalent amount of 2-(4-morpholinylmethyl)cyclohexyl p-nitrobenzoate hydrochloride (m.p. 199° - 201°), there is obtained the 2-(4-morpholinylmethyl)-cyclohexyl p-aminobenzoate hydrochloride, melting at 215° - 217° after crystallization from acetonitrile.

EXAMPLE 8

15 Parenteral Formulation

A sterile powder for reconstitution for parenteral use is prepared from the following ingredients:

2-(Diethylaminoethyl)cyclohexyl p-aminobenzoate hydrochloride	100 mg.
Benzyl alcohol	150 mg.
Sodium chloride	35 mg.

The sterile powder is aseptically blended and filled into ten sterile vials, each containing 28.5 mg., and sealed. The addition of 1 ml. of water for injection to the vial provides a solution of intramuscular injection.

EXAMPLE 9

30 Parenteral Formulation

A preformed solution is prepared from the following ingredients which supply ten vials each containing 15 mg. of active ingredient in 1 ml. of water for intramuscular injection:

2-(Diethylaminoethyl)cyclohexyl p-aminobenzoate hydrochloride	150 mg.
Benzyl alcohol	150 mg.
Sodium chloride	30 mg.
Water for injection	q.s. to 10 ml.

40 The solution of the foregoing ingredients is filled into ten sterile vials, each containing 1 ml., sealed and stored under refrigeration.

EXAMPLE 10

45 Oral Tablet

The following ingredients are thoroughly mixed in a Hobart blender:

50 2-(Diethylaminoethyl)cyclohexyl p-aminobenzoate hydrochloride	1,000 mg.
Corn starch	1,125 mg.
Lactose	8,000 mg.
Magnesium stearate	100 mg.
Avicel (microcrystalline cellulose)	2,250 mg.

55 The blended mixture is then compressed into tablets in normal manner to make 100 tablets.

What is claimed is:

1. A method of stimulating the central nervous system comprising administering to humans an effective amount of a compound of the formula

or a pharmaceutically acceptable acid addition salt thereof, wherein n is 0, 1 or 2, R is hydrogen or lower alkyl of up to 4 carbon atoms, R_1 is lower alkyl of up to four carbon atoms, and R and R_1 together with the nitrogen atom to which they are bonded are piperidino, morpholino or pyrrolidino.

2. A method of stimulating the central nervous system comprising administering an effective amount of a compound of claim 1 in combination with a pharmaceutically acceptable carrier.

3. A method according to claim 1 wherein the

amount of compound administered is about 1 mg. to about 50 mg.

4. A method according to claim 3 wherein the amount administered is from about 5 mg. to about 20 mg.

5. A method according to claim 1 wherein R and R_1 are each alkyl and wherein the number of carbon atoms in R and R_1 is at least 3.

6. A method according to claim 5 wherein R and R_1 are each ethyl.

7. A method according to claim 6 wherein n is 1.
